Term of patent 14 years

(Cl. D80—9)

To all whom it may concern:

Be it known that I, Joseph A. Anderle, a citizen of the United States and a resident of Westerleigh, S. I., in the county of Richmond and State of New York, have invented a new, original, and ornamental Design for a Venetian Blind Display Stand, of which the following is a specification, reference being had to the accompanying drawing, forming part thereof.

The figure of the drawing is a perspective view of a Venetian blind display stand embodying my new design.

The portions not shown are the same as like portions shown in the figure.

I claim:

The ornamental design for a Venetian blind display stand, substantially as shown and described.
